OXIDATION OF SATURATED ALIPHATIC HYDROCARBONS TO KETONES

Nat C. Robertson and James H. Gardner, Cambridge, and Albert Di Nardo, Jamaica Plain, Mass., assignors, by mesne assignments, to Escambia Chemical Corporation, Pace, Fla., a corporation of Delaware

Application September 2, 1952, Serial No. 307,414

4 Claims. (Cl. 260—597)

This invention relates to the production of chemicals and more particularly to the production of oxygenated hydrocarbons by the air oxidation of normally gaseous saturated hydrocarbons.

A principal object of the present invention is to provide a process for the oxidation of normally gaseous saturated hydrocarbons to produce high yields of ketones.

Another object of the invention is to provide a process of the above type which is particularly adaptable to the production of high yields of acetone.

Still another object of the invention is to provide a process of the above type which provides for the selective oxidation of normally gaseous saturated hydrocarbons, having one tertiary hydrogen atom, in such a way that there is no net yield of the expected tertiary alcohol.

Still another object of the present invention is to provide an improved process for the oxidation of isobutane in which there is no net yield of tertiary butyl alcohol.

Other objects of the invention will in part be obvious and will in part appear hereinafter.

The invention accordingly comprises the process involving the several steps and the relation and the order of one or more of such steps with respect to each of the others which are exemplified in the following detailed disclosure, and the scope of the application of which will be indicated in the claims.

For a fuller understanding of the nature and objects of the invention, reference should be had to the following detailed description and the accompanying drawing which is a diagrammatic flow sheet illustrating one preferred method of practicing the invention.

In the present invention a normally gaseous saturated hydrocarbon, containing one tertiary hydrogen atom, is oxidized at a relatively high pressure to produce predominantly ketones as final reaction products. The method comprises the steps of dissolving the gaseous hydrocarbon in a tertiary alcohol. In a preferred embodiment of the invention the normally gaseous hydrocarbon is isobutane and the solvent is tertiary butyl alcohol. To accomplish the oxidation an elemental-oxygen-containing gas is passed through the solution while the solution is held under pressure. During oxidation the solution is maintained at a temperature above about 145° C., while the oxygen-containing gas passes therethrough. Thereafter the oxygenated hydrocarbons are separated from the solution.

While the oxidation of normally gaseous saturated hydrocarbons in solution is not new, it has been found that the method of practicing the present invention provides particularly advantageous results, since ketones rather than alcohols are the final reaction products. When isobutane is oxidized in a solvent such as benzene, the principal reaction product is tertiary butyl alcohol. However, when tertiary butyl alcohol is employed as the solvent, it has been found that there is no net gain of tertiary butyl alcohol, the final reaction product comprising primarily ketones and, in particular, acetone.

While the invention will be specifically described here-

2

inafter as applied to the oxidation of isobutane, it is equally applicable to other hydrocarbons having one tertiary hydrogen atom. One preferred embodiment of the invention is set forth in the following nonlimiting example.

Example 1

Thirteen hundred grams of tertiary butyl alcohol together with 1.4 grams of manganese propionate and 40 cc. of a pH 5 phosphate buffer solution are charged to a high pressure reactor 10. Eight hundred and fifty grams of isobutane are passed through the reactor and the reactor temperature is raised to 125° C. Air is fed until the pressure reaches 690-710 p. s. i. the temperature being raised to 175-180° during this addition. A steady rate of air feed of about 4 standard cubic feet per hour is commenced, an automatic pressure relief valve venting nitrogen, oxides of carbon and a small amount of uncondensed reactant downstream of a condenser 12 to maintain 700 p. s. i. Isobutane is fed at varying rates to replenish the consumption. 412 grams of isobutane are fed in this manner during a six hour run.

After termination of the run the reaction mixture is neutralized and fractionated to obtain the following materials:

Acetone 127.1 grams; tertiary butyl alcohol 1237.8 grams; methanol 11.8 grams; methyl acetate 10.5 grams; higher esters 11.2 grams; higher ketones 9.2 grams; isobutyl alcohol 17.4 grams; mesityl oxide 6.5 grams; and formic acid 12.1 grams.

When isobutane is oxidized by air while it is dissolved in other solvents, for example benzene, it has been found that the yield of tertiary butyl alcohol under essentially identical conditions was approximately 187.5 grams compared to a yield of acetone of approximately 62.0 grams. As is apparent from a comparison of these figures with the analysis of the product set forth above, the present invention gives a much higher yield of acetone, about twice as much as is obtained under otherwise similar conditions. The increased yields of acetone which are obtained by the procedure of the present invention result in practically no net consumption or production of tertiary butyl alcohol. The small loss of tertiary butyl alcohol noted in the above specific analysis is of the order of handling losses.

When the process is operated on a continuous basis, the condenser 12 continuously refluxes isobutane, tertiary butyl alcohol and other oxygenated products to a water scrubber 14. The refluxed isobutane is separated from the remainder of the reflux in the scrubber 14 and is recycled to the bottom of the reactor 10. From the scrubber 14 the reflux and the scrubbing water are directed into a distillation separation apparatus 16 (which may include several conventional stills) where the contained water and various reaction products are removed from the tertiary butyl alcohol contained in the reflux stream. This tertiary butyl alcohol or its water azeotrope is also recycled to the reactor 10.

As can be seen from the drawing, some of the liquid in the reactor 10 is also fed to the distillation separation apparatus 16 so as to provide for continuous removal of the various oxygenated products which are not carried off as vapors and condensed in the reflux condenser 12.

While one specific example of the present invention has been given above, it is subject to wide variations without departing from the scope thereof. For example, the manganese propionate (of about 0.1% concentration) is a well known oxidation catalyst. Other manganese salts or salts of oxides of metals of variable valence are equally effective. An important purpose of utilizing an oxidation catalyst is to prevent the creation

of large concentrations of dangerously explosive hydroperoxides. It is believed that the metal walls of the reaction chamber may have sufficient catalytic effect to prevent the formation of such hydroperoxides. Similarly, while the use of a phosphate buffer solution (which is obtained by titrating a solution of trisodium phosphate with phosphoric acid) is quite effective, numerous other well-known buffer solutions may be employed. The range of operating pressures and operating temperatures is quite broad and can be varied within considerable limits.

With regard to pressure it should be pointed out that it is preferably maintained above 300 lbs. per square inch, but that considerably higher pressures may be utilized where design considerations indicate the desirability of such higher pressures. The temperature within the reactor 10 may be varied between about 145° C. and about 200° C. or higher. The same general conditions apply with respect to rates of feed of the constituents into the reactor. About the only limitations upon such feed are the difficulty of temperature control and the undesirability of permitting any appreciable concentrations of oxygen in the space above the liquid phase. The presence of oxygen in this space would constitute a definite operating hazard.

While the above invention has been specifically described in terms of the oxidation of isobutane, it is equally applicable to other hydrocarbons of molecular weight of C₈ or less containing only one tertiary hydrogen atom such as isopentane or isoctane. Equally, the tertiary alcohol has been described as tertiary butyl alcohol. This may be replaced by the tertiary alcohol normally constituting the first reaction product of, for example, the isopentane or the isoctane. In these latter two cases the tertiary alcohols would be tertiary amyl alcohol and 2,2,4-trimethyl-pentanol-4, respectively.

Since certain changes may be made in the above process without departing from the scope of the invention herein involved, it is intended that all matter contained in the above description, or shown in the accompanying drawing, shall be interpreted as illustrative and not in a limiting sense.

What is claimed is:

1. A method of oxidizing a saturated hydrocarbon having from 4 to 8 carbon atoms and containing at least one tertiary hydrogen atom to produce ketones which comprises dissolving said saturated hydrocarbon in a tertiary alcohol having the same number of carbon atoms as said saturated hydrocarbon, passing an elemental-oxygen-containing gas through said solution while said solution is held under pressure, maintaining said solution at a temperature above about 145° C. while said gas passes therethrough, and separating ketones from said solution.
2. A method of oxidizing isobutane to produce a high yield of acetone with essentially no net production of tertiary butyl alcohol which comprises dissolving isobutane in tertiary butyl alcohol, passing an elemental-oxygen-containing gas through said solution while said solution is held under pressure, maintaining said solution at a temperature above about 145° C. while said gas passes therethrough, and separating acetone from said solution.
3. The method of claim 1 wherein said saturated hydrocarbon is isoctane and said tertiary alcohol is 2,2,4-trimethyl-pentanol-4.
4. The method of claim 1 wherein said saturated hydrocarbon is isopentane and said tertiary alcohol is a tertiary amyl alcohol.
